UNITED STATES PATENT OFFICE

JONAS E. WINEGARNER, OF WARRENSBURG, ILLINOIS

BLOWER-PIPE ATTACHMENT

Application filed May 21, 1928. Serial No. 279,545.

This invention relates to an attachment for a blower pipe such as is used in connection with a grain thrashing machine.

As is well known, this pipe conveys a current of air under pressure, which serves to carry off the chaff, straw and the like. This loose material is ordinarily stacked in the field for subsequent use. In building the stack however, there is no means to regulate 10 the size and shape thereof, particularly on the rear side. For example, when starting the stack, the loose material is carried out a distance from the discharge end of the blower pipe, until the force of the air is expended. 15 Hence the material on the rear of the stack is usually loose, and easy blown away in wind and rain storms.

What I propose to provide is an attachment which includes a movably mounted back stop, 20 such as can be raised and lowered to cooperate with the discharge end and to aid in shaping and building the stack, so that it assumes a different shape, and the material is packed more firmly.

25 Other features and advantages of the invention will become apparent from the following description and drawings.

In the accompanying drawings, wherein like reference characters are employed to 30 designate like parts of the same:—

Figure 1 is a side elevational view of the discharge end of the blower pipe showing the attachment in position thereon with the back stop in lowered position.

35 Fig. 2 is a top plan view of the same.

Fig. 3 is an end view of the flexible back stop.

Fig. 4 is a cross section taken approximately upon the plane of the line 4—4 of Fig. 40 1, looking in the direction of the arrow.

Fig. 5 is a fragmentary perspective view of one of the supporting arms for the back stop.

Fig. 6 is a cross section taken approximately upon the plane of the line 6—6 of Fig. 1.

45 Referring to the drawings by numerals, it will be observed that the reference character 7 designates generally a back stop. This comprises a cross bar 8 carrying a plurality of depending chains 9, suspended therefrom in longitudinally spaced relation. These

chains are free at their lower ends to permit them to serve in an efficient manner without becoming entangled with the loose material.

The cross bar 8 is attached to a pair of spaced parallel arms 10 disposed on opposite sides of the discharge end portion of the blower pipe 11. At 12 and 13 are appropriate braces for rendering the structure rigid.

As better shown in Fig. 4, a split band 14 embraces and is fastened to the pipe adjacent the downturned discharge end. This band is provided with diametrically opposite right angular brackets 15 having openings for accommodating the connecting and pivot pins 16 (see Fig. 5). It will be observed that by providing a series of these pins, the arms can be adjusted longitudinally to vary the distance between the back stop and the discharge end of the blower pipe.

Moreover, the pins are separably connected with the brackets so that the entire swinging structure can be removed from the pipe. Attached to the inner end portions of the arms, as better shown in Fig. 6, is a stirrup 17 whose arms 18 are pivoted to the arms 10 as at 19. The purpose of this stirrup is, principally, to limit the swinging position of the inner end portions of the arms 10 as shown in Fig. 1. This of course, limits the downward or lowermost position of the flexible back stop 7.

It will be observed that the bight portion 20 of the stirrup is formed with a keeper seat 21, carrying an eye or ring 22. The purpose of the eye is to permit the hooked end of a pull rod 23 to be connected therewith as shown in Fig. 1, so that the operator on the ground may pull downwardly on the rod to lift up on the back stop.

When the yoke is thus pulled downwardly, it is held down by the action of a small latch 24, the lower end of the latch being notched and engaging in the keeper seat 21, as shown plainly in Fig. 6. The latch is pivoted between the split ends 25 of a ring 26 which surrounds the pipe. Incidentally this ring is provided with a guide 27 through which the arms 18 of the yoke extend.

Obviously, as the yoke is pulled down by the rod 23, the latch 18 swings down on its

5 pivot and the notched end thereof engages in the keeper seat 21, to hold the yoke down. This in turn, holds the arm 10 in the horizontal dotted position shown in Fig. 1. Therefore, the back stop has a lower position and an upper position, and it can be moved intermediately through the use of the rod 23.

10 To begin with, the back stop is lowered so that as the loose material is blown out from the pipe under the action of the wind pressure, the same backs up against the back stop and is started in a pile. Then by proper manipulation of the back stop, the loose material can be piled into a firm and properly shaped stack.

15 Minor changes in shape, size, and re-arrangement of parts coming within the field of invention claimed may be resorted to if desired.

20 Having thus described my invention, what I claim as new is:—

1. In a structure of the class described, a back stop, a pair of spaced parallel attaching arms, means for adjustably and detachably connecting said arms with a blower pipe, a yoke pivotally mounted upon the inner end of said arm and adapted to limit swinging movement of the arms in one direction, 30 together with a gravity lowered pivotally mounted latch cooperable with said yoke, for holding the yoke in its lowermost position.

2. An attachment of the class described, comprising a backing member embodying a cross head, and a plurality of flexible chains carried thereby, a pair of attaching arms connected to the cross head and disposed in spaced parallelism, and adapted to occupy a position on opposite sides of a blower pipe, 40 a band adapted to embrace the blower pipe and provided with apertured brackets, pins carried by said arms adapted to be selectively arranged with the apertures in said brackets, a yoke pivotally mounted upon the inner 45 ends of said arms, said yoke having its bight portion formed with a keeper seat, a gravity lowered pivotally mounted latch, means for mounting the latch on the blower pipe, said latch being associated with said keeper seat, whereby to hold the yoke in a predetermined position.

In testimony whereof I affix my signature.
JONAS E. WINEGARNER.
